Leonard R. Bradley, Cumberland, R.I., assignor to Texas Instruments Incorporated, Dallas, Tex., a corporation of Delaware

Filed Sept. 25, 1968, Ser. No. 13,921

Term of patent 14 years

Int. Cl. D10—07

U.S. Cl. D52—7

Fig. 1.

Fig. 2.

FIGURE 1 is a perspective view of one embodiment for my new design of a thermostat.

FIGURE 2 is a perspective view of a second embodiment of the thermostat.

The undisclosed side of the thermostat is a mirror image of the side shown, and the bottom is substantially the same as the top, the rear of the thermostat being substantially plain.

The dominant features of my new and ornamental design are shown in solid lines in the drawing.

I claim:

The ornamental design for a thermostat, substantially as shown and described.
